UNITED STATES PATENT OFFICE.

MORRIS MARCUS MILLS, OF SAN ANTONIO, TEXAS.

DESIGN FOR A DISPLAY-STAND.

57,705.

Specification for Design.

Patented Apr. 26, 1921.

Application filed October 11, 1920. Serial No. 416,320. Term of patent 14 years.

To all whom it may concern:

Be it known that I, MORRIS MARCUS MILLS, a citizen of the United States, residing at San Antonio, in the county of Bexar and State of Texas, have invented a new, original, and ornamental Design for a Display- Stand, of which the following is a specification, reference being had to the accompanying drawings, forming a part thereof.

The figure is a perspective view of a display stand, showing my new design.

I claim:

The ornamental design for a display stand as shown.

MORRIS MARCUS MILLS.

Witnesses:

C. DALKOWITZ,
W. J. SCHWARTZ.
